UNITED STATES PATENT OFFICE.

OTHMAR MAYCEN, OF NEW YORK, N. Y.

WASHING MACHINE.

Application filed June 20, 1927. Serial No. 200,172.

This application is in part a continuation of the one filed by me on the 9th day of May, 1927, under Serial No. 189,952 and relates to an improvement of my new washing machine described in my aforesaid prior application.

The improvement forming the subject matter of this present application over the prior one consists in the addition of certain new parts arranged and combined with the other parts in a new manner as to allow a finer regulation of the work of the machine and the optional utilization of the device without the operation of its power generating parts, simply for rinsing purposes.

With these ends in view, the improvement is brought about by giving the shell of the machine a somewhat different shape, bringing the container for the solid soap spacedly in a different relation with the main chamber of the shell, rendering the shaft, carrying the members for imparting motion, hollow and arranging within the soap box a plate valve so as to close or open at will the various apertures establishing connections between the soap container and the city water with the main chamber of the shell.

For the better understanding of my invention, reference is had to the accompanying drawings in which

Figure 1 is a top view of my new and improved washing machine, a part of the outer shell having been broken away so that the movable parts arranged within may be inspected. Figure 2 is a top view of the device turned 90° around its longitudinal axis and having one-half of the shell entirely removed thereby laying bare all the inside parts of the machine. Figure 3 is a fragmentary vertical sectional view of the bottom of the compartment inserted into the main chamber of the machine. Figure 4 is a vertical sectional view of the water supplying means along line 4-4 of Figure 2. Fig. 5^a is a top view of the plate valve, Figures 5^b and 5^c are perspective views of the said plate and of an elastic washer, respectively. Figures 6^a, 6^b and 6^c are detail views of a button to operate the plate valve. Fig. 7 is a top view of the machine similar to Fig. 1. Fig. 8 is a similar view as that of Figure 2. Fig. 9 is a front view of the mouth of the shell, showing the front part of a new type of support for the shaft. Fig. 10 is a rear view of said support and

Fig. 11 is a view of another form of turbine wheel. Like numerals denote like parts.

In the drawings 10 denotes a hollow shell, having the shape of a bottle, consisting of a compartment or rear chamber 11 in the form of a cylindrical box tightly inserted into the front chamber 12 and held therein by any well known means (not shown). In the center of the pointed end of the bottle, an aperture 13 is provided through which a hollow shaft 14 is inserted in such manner that it coincides with the longitudinal axis of the shell.

The aperture 13 is furthermore surrounded by a plurality of perforations 15 through which water flows out while the power generating means of the machine are in action. The inside wall, or bottom of the rear chamber 11 has a centrally disposed aperture 16 drawn out into a nozzle 17 over which the inside end of the hollow shaft 14 is loosely slipped.

A gearwheel 18 is rigidly secured to the hollow shaft 14, the teeth of which engage the basket shaped turbine wheel 19 dented in at its central part. A bracket 20, consisting of a wire 23 flattened out at its upper part and having an aperture in which the hollow shaft 14 is journaled, is secured inside to the wall of the shell 10 and passed operatively through the center of the turbine wheel 19; the wire 23 terminates shortly above the wall of the shell 10, where a screw 21, passed through the wall, engages the screw threaded bore within the lower terminal of the wire thereby holding the bracket 20 rigidly in the proper position.

Around the deepest point of the dented in part of the turbine wheel 19 a set of annularly arranged holes 24 is provided, said holes 24 engaging the teeth of the above mentioned gear-wheel 18. A short nipple 22 surrounds the wire 23 and supports the turbine wheel 19 between its center and the line of holes 24.

The outside or rear wall of the rear chamber 11 has an inwardly directed screw threaded neck 25 which is engaged by the screw-threaded end 26 of a handle 27, a knurled rim 28 being provided close to the screw thread of the handle so as to facilitate the tightening of the handle within the neck 25.

A tube 29 is provided centrally within the handle 27; it terminates in front of the aperture 16 and in the rear it protrudes out of

the handle and is there connected with a rubber tube 30 which suitably is connected to a water faucet (not shown).

- 5 A plate 31 is interposed between the bottom of the rear chamber 11 and rotatably arranged on a rivet 32, which passes approximately through the center 32^a of the said plate 31 and is rotatably supported in the end wall of the chamber 11; furthermore an 10 elastic washer 33, (see Fig. 6^c), is interposed on the inner side between said plate 31 and the head of the rivet 32 so as to constantly press the plate 31 on the bottom of the rear chamber 11. Besides the aperture 16, in the plane of the middle of the height of the turbine wheel 19, the rear chamber 11 has another aperture 34 in a distance slightly less than the radius of the turbine wheel 19 from the aperture 16 15 so that the aperture 34 is only slightly below the highest point of the turbine wheel 19 and a line between said aperture 34 and said highest point is substantially parallel to the axis of the hollow shaft 14. The 20 aperture 35 in the lower left corner of the plate 31 is equidistantly disposed from the rivet, or the aperture 32^a provided for the same in the plate 31, as the aperture 34 from the rivet, and the aperture 36 is disposed 25 substantially vertically above 32^a in the same distance as the aperture 16 from the rivet 32. The aperture 36 has suitably a diameter of 3/16", the aperture 35 is furthermore suitably covered with a wire gauze. 30 Both the plate 31 and the washer 33 have at their ends adjoining the tube 29 a slightly curved projection 37 and 38, respectively, approaching the said tube 29 and extending along the same for a short distance. 35 Near the end of these projections preferably a plurality of passageways 39 are provided, these passageways being directed transversely through the wall of the said pipe 29. 40 On top of the shell 10 a slot 40 is provided extending equidistantly on both sides of the shaft 14, a scale 42 extending along said slot, which furthermore is provided with four round incisions 41, opposite the four 45 imprints "Stop"—"Clean"—"Soap"—"Power", into which the shank of the button is pressed during the shifting of the valve. 50 Opposite to projection 37 and on the opposite side of the plate 31 a lever 43 is slipped over a flattened portion of the shank of the rivet 32, said lever terminating in the form of a bracket within the main space 12, shortly below the shell 10, and the screw threaded shank of a button 44 is arranged 55 through the slot 40, in said bracket of the lever 43, an elastic spring 45 having been interposed between the button 44 and the upper side of the shell 10, the finger 45^a of the said spring resting on the scale 42. 60 65 The front part 46 of the hollow shaft 14,

projecting from the main part 12, is pressed flat and undulated on its surface. A brush 47 is slipped over the undulated part 46 and held by the same; the brush is made of double spirals in so far as it has for the first the spiral given the bristles by the twist of the wires, and in addition thereto, the simple brush thus obtained is wound up once more in a helical line or spiral.

The operation of the device is as follows: 75 At the beginning of the operation the finger 45^a stands at "Stop" which means that the plate 31 fully covers both the apertures 16 and 34 in the bottom of the rear chamber 11. If I now push the button 44 so that 80 the finger 45^a stands at "Clean" the aperture 36 of the plate 31 fully registers with the aperture 16 so that, the faucet having been turned on before, the water directly passes through the pipe 29, the nozzle 17, the hollow shaft 14 out of the orifice of the front part 46. In this case the water flowing out of 46 is only used for rinsing, and as the water follows the law of the least resistance, water flows neither into the rear chamber 11, which is filled with pieces of solid soap, nor flows water of any amount 85 out of the said rear chamber 11, and the water flowing out of 46 is therefore practically pure water. If I now move the button 44 so that the finger 45^a stands at "Soap", the aperture 36 of the plate 31 only partially registers with the aperture 16 so that the plate 31 covering part of 16 acts as a baffle plate to the water, forcing same back 90 so that it flows out of the aperture 39 through the rear chamber 11 filled with soap. Owing to the transverse direction of these apertures 39, the water flowing out of the same is whirled around in the rear chamber 11, thereby dissolving the soap very efficiently. As now the projections 37 and 38 of the plate 31 and of the washer 33, respectively, are very little curved so as to be almost flat, there is enough open left around the orifice of the pipe 29 that the soapy water formed in the rear chamber 11 can leave through the only partially open aperture 16. 100 105 110

If I want to use power, it is natural that I want it only in such case where some friction has to be exerted on the surface of the dishes or any other articles, f. i. also of automobiles, because then I want to remove any grease or remainders of food etc., which adhere to the surface and naturally I want to use soap because it greatly facilitates such work. I have succeeded by my new improvement to solve this problem in a simple and efficient manner.

In order to use power in my work I generate the same by my new machine by moving the button 44 so that the finger 45^a stands at "power". The position of the plate 31 is then such that it closes entirely 115 120 125 the aperture 16, but the aperture 35 of the 130

plate 31 now fully registers with the aperture 34 in the bottom of the rear chamber 11. Now, however, no water at all can flow out of the orifice of pipe 29 and all the water 5 flows through the transverse apertures 39, whirls then through the rear chamber 11 thereby dissolving soap and the soapy water is then forced with it full pressure through the aperture 34 upon the highest 10 inner point of the pockets of the turbine wheel 19, thereby imparting motion to the same, which motion is then transferred to the gear 18 driving the shaft 14 and causing the brush 47, slipped over the front part 15 46 of shaft 14, to rotate. Owing to the novel arrangement of the double spiral of this brush 47, described above, this brush 47 acts as an endless screw conveyor and materially facilitates in the removal of any matter 20 adhering to the surfaces to be washed.

If lever 43 is not shaped in such manner as to lay open hole 34, it must be provided with a hole which must register with the aperture 34 so as to make the way free for 25 the water.

The plate valve 31, instead of being rotatably secured to the bottom of the compartment, may be substituted by a plate valve which is simply shifted back and forth 30 along the bottom, or a valve having a round body, it is obvious that the valve may be used for regulating the pressure of the water by opening more or less the apertures 35 and 36; this is done by putting the finger 45^a to any desired point between any 35 of the corresponding marks of the scale.

It is obvious also that various changes can be brought about in the construction of the machine without deviating from or sacrificing 40 the advantages of the construction. Such a change is for instance shown by the Figures 7, 8, 9, 10 and 11 which show some parts of the machine in a somewhat modified form.

Without changing the water supplying means and the means regulating the flow of the water through the compartment, which 45 is also entirely unchanged, a material effect is brought about by the change of the means supporting the turbine wheel 19.

The turbine wheel 19^a is also made out of one piece like the wheel 19, but is changed around the center of the bottom in so far as an annular ring 48 is pressed inwardly, 50 while the sheet metal within this ring 48 is pressed outwardly so as to depend somewhat below the bottom of the wheel and to form a basket shaped hub 49. The annular ring 48 is provided with holes 24 exactly as 55 the turbine wheel 19.

Furthermore a strip of flat iron 50 is bent into a frame having a semi-circular front bow 51, which extends along the curvature of the bottle into a straight support 52, and 60 finally into an arm 53.

The front bow is provided with an aperture 54 and the upright arm 53 with an aperture 55, the hollow shaft 14 being journaled in said apertures 54 and 55. The bent iron strip 50 is secured at the front by two screws 70 and in the rear by a screw set into the bottom of the compartment or rear chamber 11.

The turbine wheel 19^a is rotatably secured to the straight portion 52 by means of a rivet 56 passed through the central aperture provided in the basket shaped hub 49, the turbine wheel 19^a being spaced so disposed as to have its teeth engage those of the gear wheel 18.

The strip of the bow 51 divides the mouth of the bottle in two apertures which allow the water to flow through and so this construction allows to dispense with the special steps in the manufacture to provide the apertures 15. It is also evident that further 85 facilities, in the manufacture are obtained, as the whole arrangement of the inside parts is attached to the compartment 11 and that all these so connected parts can be taken in or out together by simply opening or fastening the screws holding the front bow 51.

What I claim is:

1. In a washing machine the combination of a bottle shaped shell open at its large end, an axially disposed hollow rotary tool shaft, projecting from said shell at its neck and mounted within the shell, gearing secured to said shaft, water actuated means engaging said gearing, a compartment tightly inserted into and held within the 100 rear part of the aforesaid shell, an opening in the outside wall and a central aperture in the inside wall of said compartment opening into said shell, a handle detachably secured in the opening of the outside wall, 105 a tube passing through said handle and being adapted to be connected to a water supply and terminating closely to aforesaid aperture, another aperture in the inside wall of aforesaid compartment for directing a 110 stream of water against said water actuated means, a slot in the side of the shell, a plate valve for controlling the flow of the water, rotatably secured to the inside wall of the compartment, and a double spiral brush attached to the front of the hollow tool shaft.

2. In a washing machine the combination of a bottle shaped shell open at its large end, an axially disposed hollow rotary tool shaft projecting from said shell at its neck and mounted within the shell, gearing secured to said shaft, water actuated means engaging said gearing, a compartment tightly inserted into and held within the rear part 125 of the aforesaid shell, an opening in the outside wall and a central aperture in the inside wall of said compartment opening into said shell, in the form of a nozzle projecting into aforesaid hollow shaft, a handle detachably 130

secured in the opening of the outside wall, a tube passing through said handle and being adapted to be connected to a water supply, terminating closely to aforesaid central aperture, another aperture in the inside wall of aforesaid compartment for directing the stream of water against said water actuated means, a slot in the side of the shell, a plate valve for controlling the flow of the water rotatably secured to the inside wall of the compartment, and a double spiral brush attached to the front end of the tool shaft.

3. In a washing machine the combination of a bottle shaped shell open at its large end, an axially disposed hollow rotary tool shaft, projecting from said shell at its neck, gearing secured to said shaft, a turbine wheel engaging said gearing, a compartment tightly inserted into and held within the rear part of aforesaid shell, an opening in the outside wall and a central nozzle-shaped aperture in the inside wall of said compartment projecting into aforesaid hollow shaft, a handle detachably secured in the outside wall opening, tubular means passing through said handle and terminating with one end closely to aforesaid aperture, another aperture in the inside wall of aforesaid compartment for directing a stream of water against aforesaid turbine wheel, a slot in the side of the shell, a plate valve for controlling the flow of water rotatably secured to the inside wall of aforesaid compartment, and a double spiral brush attached to the front end of the tool shaft.

4. In a washing machine a bottle shaped shell open at its large end, gearing arranged within said shell, water actuated means for driving the aforesaid gearing, a compartment inserted into and communicating with aforesaid shell at the large end, a handle engaging aforesaid compartment, water supplying means passing through said handle, a plate valve rotatably secured to the inside wall of said compartment, a brush at the front end, and an axially disposed hollow rotary tool shaft arranged within and projecting from the shell at its neck.

5. In a washing machine a bottle shaped shell open at its large end, an axially disposed hollow rotary tool shaft, gearing on said shaft, a compartment inserted into and connecting with aforesaid shell at its large end, a handle engaging aforesaid compartment, water supplying means passing through said handle, a plate valve rotatably secured to the inside wall of the compartment, a brush at the front end of the shaft, and water actuated means provided with a set of means annularly arranged around its center and engaging the aforesaid gearing.

6. In a washing machine a bottle shaped shell open at its large end, a frame secured within said shell, an axially disposed hollow

rotary tool shaft arranged within said frame, a compartment inserted at the large end into and connecting with aforesaid shell, a handle engaging the aforesaid compartment, water supplying means passing through said handle, a plate valve controlling the flow of the water, secured to the inside wall of the compartment, a brush at the front end of the shaft, a turbine wheel having a centrally disposed ring dented in its body and having the metal within aforesaid ring depend somewhat below the plane of aforesaid body so as to form a basket shaped hub, a line of apertures, engaging aforesaid gearing means, being provided in the face of aforesaid ring.

7. In a washing machine a bottle shaped shell open at its large end, an axially disposed hollow rotary tool shaft arranged in said shell, gearing on said shaft, a compartment inserted into and communicating with aforesaid shell at its large end by means of plurality of apertures, a handle engaging aforesaid compartment, water supplying means passing through said handle, a brush at the front end of said shaft, a plate valve regulating the flow of the water and provided with a plurality of holes disposed so as to register at one time with only one of aforesaid apertures.

8. In a washing machine a bottle shaped shell open at its large end, an axially disposed hollow rotary tool shaft, gearing on said shaft, a compartment inserted into and connecting with aforesaid shell at its large end by means of a plurality of apertures, a handle engaging aforesaid compartment, water supplying means passing through said handle, a brush at the front end of the shaft, a plate valve, regulating the flow of the water rotatably secured to the inside wall of said compartment and provided with a plurality of holes disposed so as to register at one time with only one of aforesaid apertures.

9. In a washing machine a bottle shaped shell open at its large end, an axially disposed hollow rotary tool shaft, rotary movement imparting means within said shell, a compartment having a plurality of apertures and communicating by the same with the aforesaid shell at its large end, a handle detachably engaging aforesaid compartment, water supplying means provided within and passing through said handle, a brush at the front end of the said shaft, a plate valve rotatably secured to the inside wall of the aforesaid compartment and having a plurality of apertures disposed so as to register one at a time with one of the apertures in the compartment, said plate valve having an elongated member projecting through a slot in the side of the shell and being adapted for operation from without.

10. In a washing machine a bottle shaped

shell open at its large end, an axially disposed hollow rotary tool shaft, rotary movement imparting means adapted to be actuated by water, a brush at the front end of the aforesaid shaft, and a compartment having a plurality of apertures in its inside wall and one opening in its outside wall, inserted into and communicating with the aforesaid shell at its large end, the inside wall of said compartment having a plate valve secured thereto so as to control the flow of the water and a handle containing water supply means engaging the opening in the outer wall.

11. In a washing machine a bottle shaped shell open at its large end, an axially disposed hollow rotary tool shaft, rotary movement imparting means arranged within said shell, a compartment inserted into and communicating with aforesaid shell by means of a plurality of apertures, a handle engaging aforesaid compartment, a plate valve having a lever projecting through a slot in the side of the shell so as to be operated from without, a brush at the front end of the shaft, a tube passing through aforesaid handle and terminating close to said plate within aforesaid compartment, said tube being provided with a set of passageways transversely directed through the wall of the tube.

30 12. In a washing machine a bottle shaped

shell open at its large end, an axially disposed hollow rotary tool shaft, gearing secured to said shaft, water actuated means engaging said gearing, a compartment inserted into and with aforesaid shell at its 35 large end, a handle engaging aforesaid compartment, water supplying means arranged within said handle, a brush at the front end of aforesaid shaft, and a frame operatively supporting aforesaid rotary shaft, said frame 40 being secured to the inside wall of aforesaid compartment and being detachably secured to the shell.

13. In a washing machine a bottle shaped shell open at its large end, an axially disposed hollow rotary tool shaft, gearing secured to said shaft, water actuated means engaging said gearing means, a compartment inserted into and communicating with aforesaid shell, a handle engaging aforesaid 50 compartment, water supplying means arranged within said handle, a brush at the front end of said shaft, and a frame operatively supporting both the aforesaid rotary shaft and the water actuated means, said 55 frame being secured to the inside wall of aforesaid compartment and detachably secured to the shell.

OTHMAR MAYCEN.
